(No Model.)

J. VOEGTLEIN.
ARTIFICIAL HAND.

No. 569,593.

Patented Oct. 13, 1896.

UNITED STATES PATENT OFFICE.

JOHN VOEGLIN, OF REPUBLIC, MICHIGAN, ASSIGNOR OF ONE-HALF TO,
GEORGE W. BARNES AND AMANDA E. BARNES, OF SAME PLACE.

ARTIFICIAL HAND.

SPECIFICATION forming part of Letters Patent No. 569,593, dated October 13, 1896.

Application filed March 9, 1896. Serial No. 582,447. (No model.)

To all whom it may concern:

Be it known that I, JOHN VOEGLIN, residing at Republic, in the county of Marquette and State of Michigan, have invented 5 a new and Improved Artificial Hand, of which the following is a specification.

My invention is in the nature of an artificial hand; and it primarily has for its object to provide an attachment of this kind of 10 a simple and inexpensive construction, which can be easily manipulated, and which will effectively serve for its intended purposes.

My invention also has for its object to provide an artificial hand having finger members joined to a wrist portion or stock, each having an independent adjustment, whereby 15 to grasp different articles.

Furthermore, my invention seeks to provide an artificial hand having finger members 20 the movement or adjustment of which is governed by an adjusting means adapted to be operated by the other or natural hand or by contact with a table or counter.

With other objects in view, which will hereinafter be referred to, my invention consists 25 in an artificial hand constructed in substantially the manner first described in detail, and then specifically pointed out in the appended 30 claims, reference being had to the accompanying drawings, in which—

Figure 1 is a view illustrating my invention as in use. Fig. 2 is a side view of the hand. Fig. 3 is a plan view thereof. Fig. 4 is a side view of one of the fingers. Fig. 5 is a similar 35 view taken from the opposite side of the same.

In its practical construction my invention comprises four finger members A A' A² A³ and a thumb member A⁴, all of which are constructed substantially alike, the fingers being 40 arranged to operate in a like manner, while the thumb member is arranged to close up in a direction opposite to the closing movement of the fingers.

As the several finger members are constructed to operate practically alike, a detailed description of one of such members 45 will suffice for all.

By referring now more particularly to Figs. 3 and 4 it will be observed the finger A is 50 composed of the sections B, C, D, and E, the inner one, B, of which has its end held in a

guide-slot f in the end of the wrist or stock F, in which slot, as also in the other slots f', provided for the inner end shaft of the other members, are held to slide the guide portions 55 g g of a cuff G, having an overhanging flange g' for a purpose presently explained.

The front end of the section B is pivotally joined to the rear end of section C, as shown at c, while the said section C is joined to section D by a similar joint d, and the section D to the section E by the pivot e, the several sections B, C, D, and E having their ends lapped, as most clearly shown in Fig. 4.

The several sections B, C, D, and E are 65 relatively of such a length as to produce a finger member having knuckle-joints and portions of substantially that of a natural finger.

To provide for the independent movement 70 of the several joints of the fingers, the outer section E is connected with the section C by a toggle connection H, the fulcrum or center pivot of which is a fixed point h on the section D, as clearly shown in Figs. 3 and 5. 75 The section D is also joined to section C by a toggle-link, which is pivoted at the lower rear edge to the section D and to the forward end of a link member J, centrally pivoted to the section C and having its end j pivotally 80 connected to a link K, pivoted at k to the lower front end of the section B. To the pivot h is also secured the front end of a link L, which is pivotally joined at l to a link M, centrally pivoted to the section B and connected at m to a link N, pivotally joined to a short member g', extending outward from the slide member G.

The impact or grasping edge of the fingers are serrated or formed with projections to 90 cause them to the more securely hold an article when closed down thereon.

The wrist or stock portion F has a screw portion F', on which is held a threaded ring P, having an annular groove p to receive the 95 annular flange of the cuff member G, as most clearly shown in Fig. 3.

From the foregoing description, taken in connection with the drawings, it is thought the advantages of my invention and the manner 100 in which the same operates will be readily understood.

It will be seen that the finger members can be adjusted and moved practically like those of a natural hand, and when slipped onto an article to grasp it they can be held securely clamped thereto by turning the ring P to draw up the member G, which, as it is thus moved, holds the several toggle-links and the sections B, C, D, and E to a fixed position.

By providing a construction as shown the wearer can lean his hand upon a counter or shelf without placing his arm in any particular position.

While I have not shown it in practice, the fingers have a leather or analogous covering.

Having thus described my invention, what I claim, and desire to secure by Letters Patent, is—

1. An artificial hand consisting of a wrist portion, a series of finger members connected therewith, each formed of sections pivoted to each other and having also toggle joining means, said toggle devices being operated from the wrist portion as specified.

2. An artificial hand comprising a wrist

portion and articulated finger members having toggle devices joining same, a slidable cuff member held on the wrist portion connected with the toggle devices and means for sliding such cuff member all arranged substantially as shown and for the purposes described.

3. An artificial hand comprising a wrist portion and artificial finger members, toggle devices joining the same, a cuff member joined to such toggle devices, held to slide on the wrist portion and a screw-ring connected to the said cuff, movable on the wrist portion all arranged substantially as shown and described.

4. An artificial hand having a wrist portion articulated finger members connected therewith, and means held on the wrist portion adapted to be operated by contact with a counter or shelf as set forth.

JOHN VOEGTLEIN.
